UNITED STATES PATENT OFFICE.

CHARLES P. BUCK, OF TOPEKA, KANSAS, ASSIGNOR TO GUSTIN-BACON MANUFACTURING COMPANY, OF KANSAS CITY, MISSOURI, A CORPORATION OF MISSOURI.

AUTOMATIC VAPOR-TAKE-OFF VALVE FOR OIL TANKS.

Application filed November 13, 1922. Serial No. 600,759.

The present invention relates to vacuum controlling devices for oil tanks, and has for its particular object to devise an improved automatic valve for controlling the outlet to the pump or vapor discharge lines provided for drawing off the vapor contents from such tanks.

For this purpose I have devised an improved valve construction in which provision is made for maintaining the valve in normally open position, but of such a character that the valve is adapted to be automatically closed in response to an excessive drop in the vapor pressure within the vapor space of the tank.

With this general object in view, as well as various minor details of improvement as will hereinafter appear, the invention will now be described by reference to the accompanying drawing illustrating one form of construction which I have devised for embodying the same, after which those features deemed to be novel will be particularly set forth and claimed.

25 In the drawing—

Figure 1 is an elevation illustrating an oil tank (partly broken away) equipped with a valve constructed in accordance with the present invention;

30 Figure 2 is a plan view of the valve structure on an enlarged scale;

Figure 3 is a section taken on the line III—III of Figure 2;

35 Figure 4 is a horizontal section on the line IV—IV of Figure 3; and

Figure 5 is an enlarged detail sectional view of a portion of a valve and valve passage.

Referring now to the drawing in detail, 40 this shows the invention in its relation to an oil tank 7, from the top or deck of which extends a vapor intake pipe 8 depending within the vapor space 9 of the tank in proximity to the oil level therein. The valve construction now to be described involves certain features of improvement over a valve of similar construction as set forth in my copending application Serial No. 485,779 filed July 18, 45 1921, and comprises a valve casing 10 having an intake opening 11 for connection with the upper end of the pipe 8, and an outlet opening 12 for connection with the vapor discharge pipe 14; this pipe 14, under the action of suitable suction means, as a pump 15, 50 is designed to conduct the vapor from the

tank 7 to other tanks (not shown) for storage purposes.

Within the casing 10 is constructed a partition 16 forming a vertical valve passage having at its upper end a series of lateral ports 17 affording communication between the casing and the outlet opening 12, and the passage through said ports is controlled by means of a hollow valve or sleeve 18 which is open at both ends (see Figure 3) and provided at its upper end with a bevelled surface 19 designed for engagement with a bevelled valve seat 20 at the upper end of the valve passage adjacent to the ports 17. At the lower edge of the surface 19 the valve 18 is formed with an annular offset or recess 21 (see Figure 5) designed to provide a clearance space for any foreign matter which may be blown off the surface 19 as the valve approaches the upper limit of its movement for closing the ports 17.

Extending through the valve sleeve 18 and pivotally connected to its lower end is a supporting link 22 carrying, inside the valve sleeve, a suitable counterpoise element 23, the weight of which, combined with that of the valve, is adapted to maintain the latter normally in lowered position for opening the ports 17 into communication with the outlet opening 12. The upper end of said link 22 is pivoted to the longer arm of a lever 24 fulcrumed to the casing 10 at 25 and having its shorter arm pivotally connected with a lug 26 depending centrally from a disc 27 which in turn is clamped to the underface of a flexible diaphragm member 28. The edge of this diaphragm 28 is clamped between a circular ledge 29 formed on the casing 10 and the outer margin of a cover member 30 formed with sheltered air passages 31 to leave the outer or upper face of the diaphragm exposed to atmospheric pressure. The interior of the cover member and the adjacent portion of the casing 10 are so constructed as to afford proper clearance for the movements of the diaphragm in response to variations in the vapor pressure to which the underface of the diaphragm is subjected, and to transmit such movements through the lever 24 to the valve 18.

The casing 10 is also provided with an opening 33 in line with the valve passage formed by the partition 16 to permit access to the valve and valve seat when neces-

sary, this opening being normally closed by a suitable cap plate 34.

The function of the valve is to automatically close the ports 17 whenever the pressure of the vapor within the tank (and hence within the valve casing) falls below a predetermined point, and thereby protects the tank against any excessive vacuum being produced therein. It is obvious that the arrangement of the valve and its connections is such as to maintain the valve normally at the lower end of the valve passage, leaving the ports 17 open so long as the pressure against the lower face of diaphragm 28 is sufficient to somewhat more than counterbalance the atmospheric pressure on the outer face of the diaphragm; but as soon as this vapor pressure drops to a certain point, it is apparent that the diaphragm will be actuated in response to the unbalanced pressure on its outer face, with the result that the valve will be lifted into engagement with the seat 20. This engagement of the bevelled surface 19 of the valve against the bevelled seat 20 effects a positive closing of the valve as against the entry of any vapor or gas between the upper end of the valve and the wall of the valve passage; and the body of the valve sleeve is of such a length as to effectually oppose, by friction, any passage of the vapor between its outer face and the wall of the valve passage and prevent such vapor from reaching the ports 17 by way of the valve passage from the lower end thereof. It will also be evident that by permitting the valve to reach its seat, the diaphragm is effectually reinforced against possible rupture by the development of an excessive vacuum from any cause within the valve casing, and the diaphragm is also provided against rupture through the development of an excessive pressure by contact of the arm 24 with the top of the partition. The described construction provides an efficient pressure-responsive valve-actuating means whereby the slight movement of a diaphragm is combined with lever and link means to effect a greater amplitude of movement of the valve, and by proper proportioning of the parts the valve movement may be made as sensitive as desired.

The valve and its mechanism are all fully enclosed in compact form, so that the structure is adapted for use with any special form of seal of suitable type to protect the mechanism against unauthorized tampering.

While I have illustrated and described what is now thought to constitute the preferred form of construction, I desire to reserve the right to make such changes or modifications as may fairly fall within the scope of the appended claims.

What I claim is:

1. In combination with a tank having a

vapor discharge pipe, a valve passage open at both ends to said vapor space and provided at its upper end with lateral ports affording communication between said space and discharge pipe, said passage being formed with a valve seat adjacent to said ports, a hollow valve open at both its ends and slidably mounted in said passage and adapted to close said ports when in engagement with said valve seat, the body of said valve extending, when in closed position, to a material distance below said ports sufficient to seal the latter frictionally against vapor entering from the lower end of said passage and around said valve, and means for maintaining said valve normally in open position while permitting the same to be closed in response to a predetermined reduction in the vapor pressure within said vapor space.

2. In combination with a tank having a vapor discharge pipe, a valve passage provided at one end with lateral ports affording communication between said pipe and the vapor space within the tank, said passage being formed with a valve seat adjacent to said ports, a valve slidably mounted in said passage and adapted to close said ports when in engagement with said valve seat, said valve being formed with an offset to provide a clearance space at the lower margin of said valve seat when said valve is in closed position, and means for maintaining said valve normally in open position while permitting the same to be closed in response to a predetermined reduction in the vapor pressure within said vapor space.

3. In combination with a valve casing having a pair of openings, a valve passage provided with lateral ports affording communication between one of said openings and the interior of the casing, said passage also being formed with an interior valve seat, an open-ended cylindrical valve slidably mounted in said passage and adapted to close said ports when in engagement with the valve seat, and a pressure-actuated diaphragm constantly exposed to the pressure within the casing operatively connected to said valve.

4. In combination with a valve casing having a pair of openings, a valve passage having a port affording communication between one of said openings and the interior of the casing, a valve seat within said passage, an open-ended cylindrical valve slidably mounted in the passage and adapted to close said port when in abutment with the valve seat, a lever pivoted intermediate its length to the casing, a connection at one end of said lever to the valve, and a pressure-actuated diaphragm constantly exposed to the pressure within the casing operatively connected to the other end of said lever.

5. In combination with a valve casing having a pair of openings, a vertical tubular

passageway within said casing having a port affording communication between one of said openings and the interior of the casing, a cylindrical valve slidably mounted in the passage and adapted to close said port, an open-ended lever pivoted within the casing, a pressure-actuated diaphragm constantly exposed to the pressure within the casing pivotally secured to one end of said lever, and a connection secured at one end of said lever and pivotally mounted at its other end adjacent the lower end of said cylindrical valve.

In witness whereof I hereunto affix my signature.

CHARLES P. BUCK.
